Specification for Design.

Patented Feb. 1, 1921.

Application filed February 27, 1920. Serial No. 361,658. Term of patent 7 years.

To all whom it may concern:

Be it known that I, EMIL G. HOFMANN, a citizen of the United States, residing at Chicago, in the county of Cook and State of Illinois, have invented a new, original, and ornamental Design for Toy Sprinklers, of which the following is a specification, reference being had to the accompanying drawing, forming part thereof.

Figure 1 is a plan view of a toy sprinkler, showing my new design; and Fig. 2 is a side elevation of the same.

I claim:

The ornamental design for a toy sprinkler, as shown.

EMIL G. HOFMANN.
